[57] CLAIM

The ornamental design for an inflatable kayak, as shown and described.

DESCRIPTION

FIG. 1 is a front and left side perspective view of an inflatable kayak showing our new design;
FIG. 2 is a rear and left side perspective view of FIG. 1;
FIG. 3 is a top plan view of FIG. 1;
FIG. 4 is a bottom plan view of FIG. 1;
FIG. 5 is a left side elevational view thereof, the right side view being a mirror image of that shown;
FIG. 6 is a front elevational view thereof;
FIG. 7 is a rear elevational view thereof;
FIG. 8 is a top plan view of a second embodiment of the inflatable kayak;
FIG. 9 is a bottom plan view of FIG. 8;
FIG. 10 is a left side elevational view of FIG. 8, the right side view being a mirror image of that shown;
FIG. 11 is a front elevational view of FIG. 8; and,
FIG. 12 is a rear elevational view of FIG. 8.
